UNITED STATES PATENT OFFICE.

JOHAN ARON ALLING, OF STOCKHOLM, SWEDEN.

PEN NIB.

Application filed March 15, 1921. Serial No. 452,456.

To all whom it may concern:

Be it known that I, JOHAN ARON ALLING, a citizen of the Kingdom of Sweden, residing at Stockholm, Sweden, have invented 5 new and useful Pen Nibs (for which I have filed applications in Sweden March 20, 1920, and in Great Britain January 17, 1921, Patent No. 160,757), of which the following is a specification.

10 It has been already proposed to so construct pen nibs that both of their point members are formed with depressed portions parallel to the plane of tangency to the back of the pen, said portions being 15 continued rearwardly by outwardly inclined portions, whereby the points of the nibs obtain a soft flexibility upwardly and outwardly. It is, however, difficult to so construct such nibs as to prevent same from 20 scratching the paper when in use.

The present invention has for its object to overcome said difficulty and consists in this that the depressed portion of one of the point halves which is parallel to the 25 plane of tangency to the back of the nib is situated nearer to said plane of tangency than is the depressed portion of the other point half.

In the accompanying drawing—

30 Fig. 1 is a plan view of a pen nib constructed in accordance with this invention.

Fig. 2 is a side-elevation, with part in section, of the nib.

Fig. 3, is an enlarged cross-section taken 35 on the line 3—3 of Fig. 1.

Fig. 4 is an enlarged cross-section taken on the line 4—4 in Fig. 1.

1, 2, denote the two point halves of the nib, formed at 3, and 4, respectively, with 40 depressed portions parallel to the plane of tangency to the back of the nib, said plane of tangency being indicated by the dotted line 5, Figs. 3 and 4. The said depressed portions have for their purpose to secure a soft 45 flexibility of the nib while at the same time preventing the point from scratching the paper when in use.

The depressed portion 3 is so shaped as to allow the corresponding point half of the

nib to yield upwardly, but not outwardly. 50 To this end said portion 3 is parallel to the said plane of tangency to its whole extent. Furthermore, the depressed portion 3 is situated nearer to said plane of tangency than is the portion 4. 55

The depressed portion 4 parallel to the said plane of tangency is of less rearward extension than the depressed portion 3 and is continued rearwardly by an outwardly inclined plane portion 4, Fig. 3, thereby 60 enabling the corresponding point half to yield both upwardly and outwardly.

The said construction has proved reliable as to the avoidance of scratching of the paper, inasmuch as it is well adapted to 65 the flexibility of the nib points as is required when the writer holds the nib directed more or less forwardly or rearwardly. The point half yielding upwardly but not outwardly may be situated on the right or 70 left hand side, as the one construction or the other may be preferred according as the writer is in the habit of keeping the right hand side point half or the left hand side point half nearest to the paper in writing. 75

Having now particularly described and ascertained the nature of my said invention and in what manner the same is to be performed, I declare that what I claim is:—

1. A pen having its nib formed with depressed portions on its back at both sides of the slit, said depressed portions having a cross section parallel to the plane of tangency to the back of the nib, one of said portions being situated nearer to said plane 85 than the other portion.

2. A pen having its nib formed with depressed portions on its back at both sides of the slit, one of the depressed portions being continued rearwardly by a laterally 90 inclined surface, the other depressed portion having throughout its length a cross-section that is parallel to the plane of tangency to the back of the nib.

In testimony whereof I have signed my 95 name.

JOHAN ARON ALLING.
